UNITED STATES PATENT OFFICE

ANDREW A. HOCHER, OF ETNA, PENNSYLVANIA, ASSIGNOR TO HUBBARD & COMPANY,
A CORPORATION OF PENNSYLVANIA

METHOD OF MAKING RAIL BRACKETS

Application filed May 9, 1929. Serial No. 361,627.

This invention relates to means for supporting a third rail and more particularly to a method of making the same.

It has been the general practice heretofore to form third rail supports from a sheet of metal in such a manner that the various portions of the support are combined in a unit. This practice is undesirable in view of certain portions of the support requiring more metal than other portions and in forming the support in a unit from a piece of sheet metal a great amount of the material is wasted and it is an object of this invention to provide an improved method of making third rail supports wherein certain portions of the support are formed separately from sheet metal and the several portions welded together.

Another object of this invention is to provide a method of making a third rail support that shall reduce the cost of the finished product and such product shall be adaptable for use wherever such a support may be desired.

Other objects lie in the novel method and combination of parts as will be made apparent throughout the further description of the invention.

For the purpose of illustration, I have shown a third rail support, wherein, Figure 1 is an end view of the construction of a third rail support embodying the invention and Fig. 2 is a side elevational view partly in section of Fig. 1.

In the embodiment illustrated, the third rail support comprises a substantially circular supporting base 11 from one end of which extends a channel member 12, the upper end of the channel member 12 terminating in a bracket member 13. The bracket member 13 being adapted to support a protection board, not shown.

The center of the base 11 is provided with an inverted cup portion 14 which is adapted to extend into an opening of an insulator, not shown, the insulator being adapted to support a third rail in the usual manner. The base member 11 is provided around its edges with up-turned flanges or wings 15 for cooperating with the sides of an insulator

to maintain the same in position on the base; it will also be noted that the member 11 at one end thereof is bent in an upwardly curved direction and extends upwardly a short distance until straightened, in order that the lower edges of the downwardly extending channel portion 12 may be welded to the upwardly extending edges thereof.

The channel member 12 and the angle bracket 13 are both provided with similar flanges or wings 16 projecting from each side thereof, the wings 16 of the channel member 12 being adapted to register with the wings 15 on the base member 11.

The bracket member 13 may be formed with stepped grooves 17 or in any desired manner for cooperating with bolts or nuts for connecting a protection board thereto.

In carrying out the present method, the base 11, channel member 12 having the bracket 13 thereon and the inverted cup 14, are each formed from separate pieces of sheet metal. The base member 11 is stamped from a piece of sheet metal and is provided with the flanges or wings 15 and an opening 18 pressed or displaced upwardly in substantially the center thereof to form an upwardly extending annular edge portion. The opening 18 is provided with an upwardly projecting annular flange 19. The diameter of the annular flange 19 being substantially the same as the diameter of the cup 14. After the several pieces have been stamped to form the several members, the channel member 12 is welded to the base member at 21 and the inverted cup 14 is welded to the annular flange 19 at 22.

It will be noted that the side portion of the base member 11 which may be called the front and which is directly opposite the upwardly projecting and curving channel portion to which the lower extension of the channel member is secured at 21, has an open central portion or slotted front flange corresponding to the width between edges of the hole 18, and which at opposite ends adjacent the width thereof is flanged or winged to incline upwardly to the height of the continuous upturned flange or wing formed around the other three sides of the base portion.

The provision of the annular flange 19 around the opening 18 provides easy and ready means for welding the cup 14 to the base. Since the cup is not welded to a solid flat base, but is welded to the annular flange, the radiation of the welding heat is retarded and a more efficient weld is obtained.

The base member 11 may be provided with any number of holes 23 for receiving spikes or lag screws for attaching the support to a tie.

It can be seen from the above, that by employing the present method, a third rail support may be constructed from considerably less material than has heretofore been required, also since such supports are mostly formed from thin sheet metal, the several butt-welds may be easily and efficiently made.

The result shown in my disclosure has only been reached after a very careful and thorough study for the determination of the requirements of an improved bracket; the specific process was only worked out after a finding of important factors and just how to best maintain, control, and balance them. For example, expense; the relative strength of each element both with a view to its individual as well as its needs when in combination with others; best utilization of scrap materials, the best place and type of welding, both in view of requirements as to strength, accessibility, heat dissipation, and simplicity, all entered into the problem. In addition, the process was worked out for employment by simplified machinery; the size of the pieces, their shape, length, and type of treatment were all considered as well in my invention.

While I have illustrated and described but one embodiment of the invention, it will be apparent to those skilled in the art that certain changes in the method of making a third rail support may be employed without departing from the spirit and scope of the appended claims.

What I claim as new and desire to secure by Letters Patent is:—

1. The method of fabricating a third rail support which includes stamping out a sheet metal piece and forming a base member having an upturned flange around three sides thereof, upwardly displacing the metal in the substantial center of said base member to form an upwardly extending annular flange, forming a fourth side of the base having a slotted flange forming an inverted cup-shaped member and welding the edges of the cup-shaped member to the upwardly extending annular edges of said base member, forming a bracket member having a downwardly extending channel member terminating in an edge portion, and welding the lower edge portion of the channel member to one end of the base member.

2. The method of fabricating a third rail

support which includes stamping out a base member, an inverted cup-shaped member and a bracket member from sheet metal, upwardly displacing the metal in the substantial center of said base member, forming an upwardly extending flange around the outer edges of said base member and inclining them upwardly from the front of said base member to a given height and then at that given height around the remainder of said base member, forming an upwardly curved channel extension opposite the rear of said base member, welding the cup-shaped member to the upwardly displaced metal in the center of said base member, shaping out said bracket member to form a downwardly extending channel with flanged wings, welding the lower edges of the channel to the upwardly curved extension at the rear end of said base member for forming a unitary member.

3. The method of fabricating a third rail support which includes stamping out a sheet metal piece and forming a base member having an upturned flange around a back end and two opposite sides thereof, upwardly displacing the metal in the substantial center of said base member to form an upwardly-extending annular flange, forming a front end on the base member having an open portion substantially centrally thereof whose width corresponds to the width of the displaced center flange, forming flanges upwardly inclining from opposite extremities of such width of the front end, forming an inverted cup-shaped member, welding edges of the cup-shaped member to edges of the upwardly-extending annular-center flange of said base member, forming a bracket member having a downwardly extending channel member terminating in an edge portion, and welding the lower edge portion of the channel member to the back end of the base member.

In testimony whereof, I have hereunto subscribed my name this 3rd day of May, 1929.

ANDREW A. HOCHER.
